UNITED STATES PATENT OFFICE

147,248

DESIGN FOR A PUNCHED CARD REPRODUCING MACHINE

George H. Kress, Johnson City, N. Y., assignor to
International Business Machines Corporation,
New York, N. Y., a corporation of New York

Application May 3, 1946, Serial No. 129,305

Term of patent 14 years

(Cl. D64—11)

To all whom it may concern:

Be it known that I, George H. Kress, a citizen of the United States of America and resident of Johnson City, Broome County, New York, have invented a new, original, and ornamental Design for a Punched Card Reproducing Machine, of which the following is a specification, reference being had to the accompanying drawings, forming part thereof.

Fig. 1 is a front elevational view of a punched card reproducing machine showing my new design.

Fig. 2 is a top plan view thereof.

Figs. 3 and 4 are respectively opposite side elevational views thereof.

Fig. 5 is a rear elevational view thereof.

I claim:

The ornamental design for a punched card reproducing machine, as shown.

GEORGE H. KRESS.
